UNITED STATES PATENT OFFICE.

ERNEST H. BENNETT, OF EAST ORANGE, NEW JERSEY, ASSIGNOR TO JOHN H. BROMLEY AND EDWARD BROMLEY, COPARTNERS TRADING AS JOHN BROMLEY & SONS, OF PHILADELPHIA, PENNSYLVANIA.

DESIGN FOR A RUG.

SPECIFICATION forming part of Design No. 35,632, dated January 28, 1902.

Application filed December 26, 1901. Serial No. 87,381. Term of patent 3½ years.

To all whom it may concern:

Be it known that I, ERNEST H. BENNETT, a citizen of the United States, residing at East Orange, New Jersey, have invented and produced a certain new and original Design for a Rug, of which the following is a full, clear, and exact description, reference being had to the accompanying drawing, forming a part of this specification.

10 My invention has relation to the surface ornamentation of a woven rug; and it consists of the novel design therefor shown in said drawing. In its essentials it consists of the following distinguishing features, namely: It
15 is primarily rectangular in outline, the border being composed of parallel line figures *a*, *b*, and *c*, arranged as shown. In the field center thus formed is a central figure *d*, substantially

diamond-shaped in outline and filled in with cross-lines, and this figure *d* overlies a series 20 of line-figures *e*, arranged parallel to each other, of varying lengths and widths. The four corners of the field center are filled up with small corner-pieces, such as illustrated at *f* in the drawing.

25 I claim—

The design for a rug substantially as shown and described.

In testimony whereof I have hereunto affixed my signature this 6th day of December, 30 A. D. 1901.

ERNEST H. BENNETT.
